UNITED STATES PATENT OFFICE

JOHANNES KLEINEWEFERS, OF KREFELD, GERMANY, ASSIGNOR TO THE FIRM: JOH.
KLEINEWEFERS SÖHNE, OF KREFELD, GERMANY, A FIRM OF GERMANY

HYDRAULIC LEATHER, FABRIC, OR PAPER ROLLING MACHINE

Application filed June 10, 1929, Serial No. 369,800, and in Germany December 22, 1927.

I have filed an application for this patent in Germany, December 22, 1927.

This invention relates to hydraulic rolling machines, as for instance calenders, mangling machines and the like, and it has for its object to make it possible to regulate independently from each other the pressures on the two sides of the machine. This pressure regulation becomes necessary when irregularities occur in a sheet of fabric or paper, so that the travelling speed has to be regulated. This regulation can be effected in lever calenders by adding or removing a heavy mass on the corresponding side of the calender. In purely hydraulically operated rolling machines for strong pressures, in which cylinder journals are submitted to a common accumulator pressure, such regulation is not possible, as by such accumulator pressure all cylinder journals are uniformly influenced.

In rolling machines with combined hydraulic and lever pressure, in which several consecutive levers are connected by couplings, the pressure must with this object in view be first shut off, whereupon by shifting the coupling the lever transmission has to be altered, and then the pressure to be thrown in again.

According to the invention a separate accumulator communicating with the corresponding pressure cylinder is provided on each side of the machine, so that by changing the pressure of the one or other accumulator the desired equalization can be obtained in quite the same simple manner as in a purely lever calender. By a control known per se, the pressure water for both cylinders can be simultaneously controlled. In order that this arrangement may also be used in connection with cylinders having different diameters, the two pressure cylinders may be guided on the machine frame shiftable in the direction of pressure so that they may be adjusted for instance by means of screw spindles.

An embodiment of the invention is illustrated by way of example in the accompanying drawings in which:

Fig. 1 shows a rolling machine in side elevation,

Fig. 2 is a front elevation of a pressure cylinder.

On the uprights *a*, *b* of the machine two pressure cylinders *c*, *d* are guided shiftable in the direction of pressure. The pressure cylinders *c*, *d* are connected each by a pipe *e*, *f* respectively with an accumulator *g*, *h* respectively, the load on which accumulators can be regulated in a well known manner. Care has evidently to be taken, that the connection of the pressure pipe can follow the movement of the pressure cylinders. Each pressure cylinder has a nut *i* mounted on a screw spindle *k*, said two screw spindles adapted to be rotated by a common shaft *m* through the intermediary of worms *n* and worm wheels *o*. The adjusting of the cylinders *c*, *d* can be effected by means of a sprocket wheel *p* and a chain hanging down so that it can be easily reached.

I claim:—

A hydraulic rolling machine, comprising in combination a machine frame, pressure cylinders movably guided on said machine frame in the direction of pressure, a nut on the outer side of each pressure cylinder, a vertical screw spindle in each nut, a common horizontal shaft having two worms one for each screw spindle, a worm wheel on the top of each screw spindle meshing with the corresponding worm, and means for rotating said horizontal shaft.

In testimony whereof I affix my signature.
DR. JOHANNES KLEINEWEFERS.
